RAYMOND E. BROWN, OF PITTSBURGH, PENNSYLVANIA, ASSIGNOR TO HEYL & PATERSON, INCORPORATED, OF PITTSBURGH, PENNSYLVANIA, A CORPORATION OF PENNSYLVANIA.

HOISTING APPARATUS.

Application filed December 27, 1923. Serial No. 682,943.

The present invention relates to hoisting and conveying apparatus of the type employing a grab bucket carried by a trolley or other traversed support, such as is commonly used 5 for handling bulk materials in large quantities. There are two general styles or classes of such apparatus, one known as the man trolley type, where the operator and the bucket hoisting engine are carried by a trolley frame 10 which travels along the bridge or tower; the other known as rope system bridges or towers, where the hoisting engine is stationary at some point, the bucket being supported by a trolley with ropes passing from the bucket 15 and from the trolley to the hoisting engine and the trolley traversing engine, respectively.

The object of the present invention is to provide an improved control system for the 20 grab bucket and trolley which is equally applicable to either of the above types of apparatus.

In the accompanying drawings I have shown, for purposes of illustration only, my 25 invention embodied in a hoisting apparatus of the man trolley type, but it will be apparent from the following description that the invention is not limited in its application to this particular type of apparatus.

30 In the drawings:

Figure 1 is a plan view of the trolley;

Figure 2 is a side elevation of the trolley and grab bucket suspended therefrom;

Figure 3 is an end view of the main hoisting gear, showing one of the clutches associated therewith and the means for operating the same;

Figure 4 is a sectional view on the line IV—IV of Figure 3;

40 Figure 5 is a view, partly in elevation and partly in section, of the double acting clutch operating cylinder and parts associated therewith;

Figure 6 is a sectional view taken approximately on the line VI—VI of Figure 5;

Figure 7 is a vertical sectional view taken on the line VII—VII of Figure 5;

Figure 8 is a horizontal sectional view taken on the line VIII—VIII of Figure 3, illustrating a portion of the clutch operating means;

50 Figure 9 is a sectional view illustrating a magnet actuated valve for controlling the fluid supply to one end of the double acting cylinder;

Figure 10 is a view illustrating the brake means for one of the hold drums and the fluid pressure actuated means for releasing said brake means;

Figure 11 is a side elevation of the hoist 60 motor brake and its operating means;

Figure 12 is a detail view of the spring means for setting the hoist motor brake;

Figure 13 is a side elevation of one of the rack motor brakes and its operating means; 65

Figure 14 is a view illustrating a magnet controlled valve for regulating the pressure fluid supply to the fluid pressure cylinder associated with the rack brake shown in Figure 13;

70 Figure 15 is a view illustrating a magnet controlled exhaust valve for the fluid pressure cylinder shown in Figure 14, and

Figure 16 is a diagram showing the piping and electrical connections of the control system. 75

Referring to Figures 1 and 2, the trolley frame 3 carries the usual track engaging wheels 6 mounted upon axles 7 driven by trolley traversing or rack motors 8. The 80 trolley frame supports a grab bucket 4 and has suspended from one end thereof the usual operator's cab 5.

While the application of my improved control system, to be hereinafter described, is not 85 restricted to hoisting apparatus having any particular arrangement of drums for the bucket ropes, or any particular type of clutch means for operatively connecting the drums to the hoist motor, I prefer to employ the 90 drum arrangement and clutch means disclosed in the copending application of Hans Enard, Serial No. 664,706, filed September 25, 1923.

95 Mounted upon a shaft 9 journaled in the frame 3 are the two hold drums 10 and 11 and the closing drum 12, the hold drums being keyed to the shaft and the closing drum being mounted loosely thereon. Also mounted to rotate freely upon the shaft 9 is a main hoist gear 13, said gear being arranged intermediate the adjacent ends of the hold drum 10 and closing drum 12.

100 A ring gear 14 (Figure 4) is rotatably supported at one side of the main gear 13 upon rollers 15 mounted upon pins 16 carried by said main gear.

The main gear and ring gear are driven at the same speed by a hoist motor 17. This motor has a pinion 18 mounted upon its arma- 110

ture shaft which meshes with a gear 19 on the end of an intermediate shaft 20 journaled in suitable bearings in the trolley carriage. The intermediate shaft carries a pinion 21 meshing with the main gear 13 and also carries a pinion 22 of the same pitch diameter as the pinion 21. By reference to Figure 7, it will be seen that the pinion 22 meshes with a pinion 23 mounted upon a short shaft 24, the pinion 23 meshing with a pinion 25 journaled upon a shaft 26 beneath and parallel to the shaft 20. Another pinion 27 of the same diameter as the pinion 25 is also rotatably mounted upon the shaft 26 and is integrally connected with the pinion 25 by means of a sleeve 28. The pinion 27 meshes with the ring gear 14.

Referring to Figures 5 and 6, the pinion 23 is adapted to be moved a short distance in opposite directions from its central position, in which its axis is in the same vertical plane as the axes of the pinions 22 and 25. For this purpose the pinion 23 is operatively connected to a double acting fluid pressure cylinder 29, the piston 30 whereof has its piston rod 31 pivotally connected to one end of a pair of bars 32 arranged at opposite sides of the pinion and having the short shaft 24 extending therethrough. These bars extend through a guide 33. Each end of the shaft 24 extends through an eye 34 formed on the end of a stem 36. Each stem 36 extends through two spaced plates 37 and 38, which are slidably mounted upon a pair of parallel rods 39 projecting from an end wall of the cylinder 29. Each stem 36 is surrounded by a coil spring 40 which abuts at its ends against the plates 37 and 38 and normally maintains these plates in engagement with nuts 41 and 42 on the rods 39. These springs normally maintain the pinion 23 in its central position, in which position of the pinion both ends of the cylinder 29 are open to the exhaust.

The springs 40 will be put under compression upon movement of the piston 30 in either direction. When the piston moves to the left the eyes 34 on the stems 36 engage the plates 37 and move them to the left, thereby compressing springs 40, and when the piston moves to the right the nuts on the ends of the stems 36 engage the plates 38 and move them to the right, thereby compressing the said springs.

The opposite ends of the cylinder 29 are connected by pipes 43 and 44 with valve casings 45 and 46. These valve casings are connected by other pipes 47 and 48 to a pipe 49 connected to a suitable source of pressure fluid supply, preferably a compressed air reservoir (Figure 16). The valves in these valve casings may be operated by electro-magnets 50 and 51.

The magnet 50 is shown in detail in Figure 9, it being understood that the magnet

51 is of identical construction. It comprises a coil 52 surrounding a stationary hollow core 53. A plunger 54 is mounted in said core and carries an armature 55 upon its upper end. The lower end of the plunger 54 constitutes a valve 56 adapted to engage a valve seat in the upper end of a sleeve 57. The valve 56 is connected by a valve stem 58 with another valve 59 adapted to engage a valve seat in the lower end of the sleeve 57. The valve casing 45 has a chamber 60 therein beneath the sleeve 57 and communicating with this chamber is the supply pipe 47 leading from the source of fluid supply. The pipe 43 leading to one end of the cylinder 29 is tapped into the valve casing and communicates with the interior of the sleeve 57. The valve casing has another chamber 61 therein above the sleeve 57 and this chamber communicates with an exhaust port 62. A spring 63 in the chamber 60 engages the valve 59 to normally maintain it against its seat and the valve 56 away from its seat. Under these conditions the end of the cylinder which is connected by the pipe 43 with the valve casing is open to the exhaust. When, however, the coil 52 is energized, the armature 55 is attracted towards the core 53, thereby moving the valve 56 into engagement with its seat and the valve 59 away from its seat. This cuts off the end of the cylinder from the exhaust and places it in communication with the source of fluid supply through the pipe 43, sleeve 57, chamber 60 and pipe 47.

The operation of the parts shown in Figures 5 and 6 is as follows: Normally, as already stated, both ends of the cylinder 29 are open to the exhaust and the springs 40 maintain the pinion 23 in its central position. Let it be assumed that the magnet 50 is energized. This places the right-hand end of the cylinder 29 as viewed in Figures 5 and 6 in communication with the source of fluid supply, the left-hand end of the cylinder remaining open to the exhaust. The piston 30 is therefore moved to the left, thereby moving the shaft 24 in the same direction. The pinions 25 and 27 will, therefore, be rotated in a counter-clockwise direction through an angle corresponding to twice the amount of motion of the shaft 24, since the tooth contact between the pinions 22 and 23 serves as the fulcrum of a lever of the third class. The ring gear 14 will, therefore, be rotated in a clockwise direction, as viewed in Figure 3, relative to the main gear 13. It will be apparent that the distance moved by the teeth of the ring gear will be equal to twice the distance moved by the shaft 24. It will also be apparent that this relative movement between the ring gear 14 and main gear 13 will take place irrespective of whether the pinion 22 is being driven by the hoist motor 17 or is stationary. If, instead of the magnet 50

being energized, the magnet 51 is energized, then the piston 30 will be moved to the right and consequently the pinions 25 and 27 will be rotated in a clockwise direction and the 5 ring gear 14 will be rotated in a counter-clockwise direction relative to the main gear 13.

Referring to Figure 4, the drums 10 and 12 have flanges 63 and 64 on their adjacent ends 10 positioned within the rim of the main gear. The peripheral surfaces of these flanges constitute clutch engaging surfaces. The main gear has associated therewith a clutch for cooperation with the clutch surface of the 15 flange 63 of the hold drum 10 and another clutch of identical construction for cooperation with the clutch engaging surface of the flange 64 of the closing drum 12. Therefore, it will only be necessary for the purpose of 20 understanding the present invention to describe one of these clutches.

The clutch for cooperation with the flange 63 of the hold drum 10 is shown in Figure 3. This clutch comprises a clutch band 65 which 25 is anchored at one end upon a pin 66 carried by the main gear. The other end of this band is pivotally connected to a lever 67 pivotally mounted upon said pin. A connecting rod 68 is pivotally connected at one end to the 30 lever 67 and at its other end is pivotally connected to a lever 69 pivoted upon a pin 70 carried by the main gear. A stem 71 is pivotally connected at one end to said lever 69 and extends through an opening in a spoke 35 of the main gear. Said stem has a nut mounted upon its other end and surrounding the same between said nut and said spoke is a coil spring 72. The spring 72 normally maintains the clutch band in holding engagement 40 with the surface of the flange 63. It will be understood that in like manner a clutch of identical construction is associated with flange 64 and is normally held in holding engagement with said flange.

45 Relative movement of the ring gear 14 with respect to the main gear 13, as effected by the means disclosed in Figures 5 and 6, serves to release one or the other of the clutches as desired. For this purpose the ring gear is operatively connected to the connecting rods 68 and 68' of the respective clutches. This 50 operative connection comprises a T-shaped lever 73 (Figure 8) pivoted upon a pin 74 secured in the main gear 13 and projecting within the interior of the rim thereof. The lever 73 is hollow to receive a pin 75 which is pivoted at one end to the ring gear 14 upon a pin 76 carried by said ring gear. It will be seen that relative movement of the ring gear 60 14 in one direction or the other with respect to the main gear 13 will rock the lever 73 about its pivot 74. The lever 73 is connected by links 77 with a lever 78 pivoted upon a pin 79 carried by the main gear. The opposite 65 ends of the lever 78 extend into horizontal

slots in the connecting rods 68 and 68' and carry pins 80 and 81 which extend through vertical longitudinal arcuate slots 82 and 83 intersecting said horizontal slots. These pins are normally both positioned adjacent 70 corresponding ends of said slots 82 and 83. As shown, the pins are positioned adjacent the left-hand ends of the slots.

The operation of the clutch releasing means is as follows: Normally the clutches maintain the drums 10 and 12 operatively connected to the main gear. If it is desired to release the closing drum 12 from the main gear in order to open the bucket, for example, the magnet 51 will be energized, thereby causing 75 the piston 30 to be moved to the right and the pinion 27 to be rotated in a clockwise direction. Consequently the ring gear will be rotated in an anti-clockwise direction relative to the main gear, thereby rocking the lever 80 78 about its pivot 79. This will cause the pin 80 to engage the end wall of the slot 82 and move the connecting rod 68' to the left to release the clutch engaging the flange 64. Rocking of the lever 78 for this purpose will 85 have no effect whatever upon connecting rod 68 of the clutch engaging flange 63 of hold drum 10, for the reason that the pin 81 will simply travel in the slot 83 but will not travel far enough to engage the opposite end wall 90 of the slot 83 and move connecting rod 68 to the right. On the other hand, if it is desired to release the clutch engaging the flange 63 of hold drum 10 in order to close the bucket, for example, the magnet 50 will be 95 energized, thereby effecting movement of the piston 30 to the left. This will result in the pinion 27 being rotated in a counter-clockwise direction and the ring gear 14 in a clockwise direction with respect to the main gear. The lever 78 will therefore be rocked about 100 its pivot 79 in a direction to cause the pin 81 to engage the end wall of the slot 83 and move the connecting rod 68 of the clutch associated with the flange 63 to the left, thereby releasing 105 the hold drum 10 from the main gear. 110

The other hold drum 11, as is customary, has a brake associated therewith. In Figure 10 I have shown a brake of the character ordinarily employed, which comprises a brake band 84 engaging a rim 85 on the drum 11. One end of the band is anchored upon a pin 86 and the other end is connected to one end of a bell crank lever 87 by means of a connecting rod 88, the lever 87 being pivoted intermediate its ends upon said pin 86. The other end of lever 87 has the end of a piston rod 89 pivoted thereto, said piston rod being connected to a piston 90 working in a fluid pressure cylinder 91. A spring 92 surrounding the piston rod between an adjustable abutment 93 and the piston 90 normally maintains the brake band in holding engagement with the rim. In order to release the brake band, pressure fluid may be admitted into 115 120 125 130

the cylinder above the piston through a pipe 94 which is connected to a valve casing 95. This valve casing is connected by a pipe 96 to the source of pressure fluid supply and 5 has an exhaust pipe 97. The valve construction within the casing 95 may be identical with that within the casings 45 and 46 and may be operated by a magnet 98 of identical construction with the magnets 50 and 51.

10 A brake 99 may be associated with the armature shaft of the hoist motor 17, in order to prevent a suddenly applied reverse load on the gears and bearings that results from a sudden application of the brake associated 15 with the hold drum 11. This brake may be of the usual shoe or post type which is equally effective in both directions of rotation of the armature shaft and prevents over-travel when the power is shut off the hoist motor and the 20 brakes applied when the bucket has been hoisted to its full height. A brake of this character is shown in Figures 11 and 12 and comprises opposite brake shoes 100 pivoted to levers 101 and 102 and adapted to engage 25 a drum (shown in chain line in Figure 11) on the armature shaft of the motor. An L-shaped lever 103 is pivoted to the upper end of the lever 101, and the other arm of said L-shaped lever is connected to the upper end 30 of lever 102 by a connecting rod 104. The long arm of the L-shaped lever is pivoted at its end to the upper end of a stem 105 which extends through upper and lower spring seats 106 and 107. These spring seats are guided 35 on vertical guide rods 108, and a coil spring 109 is interposed between the spring seats and surrounds the stem 105. Upward movement of the upper spring seat 106 is limited by nuts 110 on the screw-threaded upper ends 40 of the guide rods 108. It will be apparent that the spring 109 tends to maintain the brake applied. In order to release the brake, a fluid-pressure cylinder 111 is provided, having 45 a piston 112 working therein. The piston rod 113 of this piston is pivotally connected at its upper end to the long arm of the lever 103, and the piston is positioned in the lower end of the cylinder when the brake is applied. Pressure fluid may be introduced into the 50 lower end of the cylinder through a pipe 114 to raise the piston and release the brake. This pipe may connect with the pipe 94 (Figure 16), so that the pressure fluid supply to the hold brake and hoist motor brake may be controlled by the same magnet 98.

55 A brake 115, similar to the brake 99, may be associated with the armature shaft 7 of each of the rack motors 8. One of these brakes is shown in Figure 13, parts corresponding to the parts of the brake 99 shown in Figure 11 having the same reference characters applied thereto, but with a prime affixed. This brake is released by a spring 116 arranged in the cylinder 111' beneath the piston 112', and is adapted to be applied by

pressure fluid admitted to the upper end of the cylinder through a pipe 117. The pipe 117 is connected to a normally closed exhaust valve 118 adapted to be opened by an electro-magnet 119, and the said pipe is connected to the pressure fluid (air) reservoir through normally open low pressure and high pressure inlet valves 120 and 121 adapted to be closed by electro-magnets 122 and 123 (Figure 16). The low pressure inlet valve is fed 75 through a reducing valve 124, and the high pressure inlet valve through a choke valve 125.

The low pressure inlet valve 120 and its electro-magnetic operating means is shown in detail in Figure 14, it being understood that the high pressure inlet valve and its operating means are of identical construction. It will be apparent that when the coil of the electro-magnet 122 is energized, the armature 126 thereof will be drawn upwardly, and the valve 120 moved into engagement with its seat by reason of the arrangement of the connecting means between the valve and armature. 90

The exhaust valve 118 and its electro-magnetic operating means are shown in detail in Figure 15. By reason of the arrangement of the connecting means between the armature 127 of the electro-magnet 119 and the valve 118, the latter will be moved away from its seat when the coil of the magnet is energized, and the armature drawn upwardly thereby, as will be apparent. 95

It will be understood that, while in the diagram of Figure 16 I have illustrated only one of the rack motors and its brake and brake controlling means, the other rack motor may be provided with identically the same 100 brake means.

Having described the construction and operation of the clutches for the hold and closing drums and of the brakes for the hold drum and hoist and rack motors, I will now proceed to describe my improved control system for these parts, reference being had to the diagram of Figure 16 which illustrates the system. 105

My control system, as applied to the above described construction, comprises the following units: A controller for the hoist motor; a controller for the trolley-traversing or rack motor or motors; the above described fluid-pressure cylinders for the brakes and clutches and the magnet controlled valves for the 115 same; contact fingers and segments in the two controllers forming parts of the circuits for the several magnets; a finger-operated switch in the rack controller handle for completing the circuit to the magnet for one of the 120 clutches; a foot-operated switch for completing the circuit to the magnet for the other clutch, and a foot-operated valve to prevent the release of the hold brake when the motor 125 brake is released when this is desired, as for 130

closing the bucket in the air or on the side of a pile where it has a tendency to fall over.

In describing my control system, I will first take up the control of the bucket, and later 5 describe the control of the rack motors.

Referring to Figure 16, conductors L and L' leading to the hoist control panel and rack control panel of the hoist and rack motors are adapted to be electrically connected with 10 the trolley rails through a main switch S. It will be understood that the hoist controller handle has the usual number of positions for controlling the speed of the hoist motor both in raising and lowering the bucket.

15 The circuit for energizing the brake magnet 98 comprises a conductor 128 tapped from the conductor L. A conductor 129 is tapped from the conductor 128 and leads to the magnet, and another conductor 130 leads from 20 the magnet to a finger 131 in the hoist controller. From another finger 132 in the hoist controller a conductor 133 leads to the conductor L'. The fingers 131 and 132 are bridged by the segments 134 and 135 when 25 the hoist controller handle is moved to any position for raising the bucket, and by the segments 136 and 137 when said handle is moved to any position for lowering the bucket, thus completing the circuit to the 30 brake magnet 98 in either case. Therefore, except for the auxiliary control of the hold brake by the operator's foot, as previously described, the hold brake and the hoist motor brake are controlled entirely by the position 35 of the hoist controller handle. In other words, putting the controller handle in any position for hoisting or lowering will release the hold and hoist motor brakes, and putting the handle in the neutral or "off" position 40 will release the pressure fluid from the brake cylinders and permit the springs to set the brake. The operator needs only to move the handle as desired to start the motor in either the up or down direction or to stop it, and 45 the brakes will be released and applied without any attention on his part beyond the normal movement of the controller handle.

Satisfactory control of either clutch cannot be obtained by the position of the hoist 50 motor controller handle alone, without either restricting the power for closing the bucket or limiting the range of speeds at which the bucket can be hoisted to less than the range normally given by the controller. Separate 55 control units being necessary for the clutches, therefore, I have found that a finger-operated switch on the rack controller handle which controls the trolley-traversing motor or motors best answers this requirement as regards the hold clutch.

60 The circuit for energizing the hold clutch magnet 50 comprises the conductor 128 leading to the magnet coil, a conductor 138 leading from the magnet coil to a finger 139 in the hoist controller, a conductor 140 lead-

ing from a second finger 141 in the hoist controller to a finger 142 in the rack controller, and a conductor 143 leading from a second finger 144 in the rack controller to the conductor L'. The fingers 139 and 141 are 70 bridged by the segments 145 when the hoist controller handle is moved to any position for raising the bucket. The fingers 142 and 144 are in contact with contact rings 146 and 147 in all positions of the rack controller handle. These rings are electrically connected through a normally open push-button switch 148 on the rack controller handle. 75

It might appear preferable to have the push-button switch 148 on the hoist controller handle on account of the clutch which it controls being associated with the hoist motor. Actual experience, however, has demonstrated that this is not the case, for several reasons. One is that it is quite customary to have an "off" position latch on controller handles, and hence it is necessary in placing an auxiliary contact on a controller handle to so select its functions that no harm will result if an operator, from force of habit, 80 presses this contact when starting to move the controller handle. If the hold clutch were unintentionally released when starting to hoist the open bucket higher, after having had it hanging in the air, the freeing of the hold drum from its connection with the motor would permit the bucket to fall, resulting in the breaking of the closing lines when they became tight, as the closing drum, 85 being connected to the motor by its clutch, could not start to turn in the downward direction. Another reason for locating the hold clutch switch on the rack controller handle is that in normal operation the rack controller handle is stationary during the 90 closing of the bucket, at which time the hold clutch must be held released, and consequently the hand that is controlling the hold clutch 95 has no other duties to perform at that time. 100

As previously stated, this auxiliary finger-operated switch on the rack controller handle closes the circuit to the hold clutch magnet, but in addition to this, the circuit passes through the contact fingers and segments in the hoist controller, so that the hold clutch can only be released when the hoist controller handle is in the proper position; that is, when power is being applied to the motor to turn it in the hoisting direction. There is one exception to this, to take care of the condition 115 when it is desirable to open the bucket very slowly, or when for any reason the bucket fails to open itself when the closing drum is freed by the release of the closing drum clutch. For this purpose, the controller is 120 provided with one point giving reverse power to the motor, and in this position, the hold clutch can be released, provided the hold brake is applied, as will be described later. 125

130 The same conditions that led to the choice

- of the rack controller handle as the safest place for the finger-operated switch for releasing the hold clutch have resulted in choosing a foot-operated switch as the best means 5 for releasing the closing clutch to permit the free opening of the bucket. This switch is in series with fingers and segments in the hoist controller which are in contact only when the controller handle is in the "off" 10 position, as it is not necessary for the bucket to be dumped while it is being hoisted or lowered. The foot-operated switch being thus inoperative except when the hoist controller handle is in the "off" position, there 15 is little danger of the bucket being dumped by the accidental pressing of this foot switch, since it is not customary to leave the bucket with a load in it when it is not in regular operation.
- 20 The circuit for energizing the closing clutch magnet 51, and including the above mentioned foot-operated switch, comprises a conductor 149 tapped from the conductor 128 and leading to the magnet coil, a conductor 150 leading from the magnet coil to the foot-operated switch 151, a conductor 152 leading from the switch to a finger 153 in the hoist controller, and the conductor 133 leading from the finger 132 to conductor L'. 25 The fingers 132 and 153 are bridged by the segment 136 and a contact 154 when the hoist controller handle is in the neutral or "off" position. It will be apparent, therefore, that depression of the foot-operated switch 151 will close the circuit to the closing clutch magnet 51 only when the controller handle is in the "off" position.

On man trolleys it is convenient to lead the pressure fluid pipes into the operator's 40 cab, and to have the magnet controlled valves for the clutches and brakes also located in the cab. This is also the case with some rope system bridges where the operator's cab is located near the main engine house. Under 45 such conditions, the preferable method of obtaining the independent control of the hold brake, which prevents its release when the hoist controller is in a hoisting or lowering position, is to provide a three-way valve in the pipe line going from the brake valve to the hold brake cylinder, leaving the motor brake cylinder connected direct to the brake valve.

In the illustrative embodiment of the 55 invention, I have shown the pipe 94 brought up close beneath the floor of the operator's cab and provided at this point with the three-way valve 155 operable by a spring-returned foot-pedal 156, whereby the valve may be moved, 60 when desired, to the position which shuts off the flow of pressure fluid to the hold brake cylinder 91 and opens a port permitting the free exhaust of the pressure fluid in the cylinder, thus permitting the hold brake to be main- 65 tained applied by its spring when the hoist

controller is in a position which normally releases the hold brake. As stated before, this is to permit the bucket to be closed in the air or on a side slope where it tends to fall over. This auxiliary control is also used when the 70 bucket is to be opened by using reverse power on the motor, which is occasionally desirable, as already explained.

The foot-pedal 156 for operating the three-way valve 155 has in connection with it a 75 push-button switch 157 which is in the circuit with the push-button switch 148 on the rack controller handle for operating the hold clutch magnet 50, so that the hold clutch cannot be released until the foot-pedal has been 80 pressed down, when the hoist controller is in the position for giving reverse power to the hoist motor. The circuit for this switch comprises a conductor 158 tapped from the conductor 138 and leading to the switch, a conductor 159 leading from the switch to a finger 160 in the hoist controller and a conductor 161 leading from a finger 162 in the hoist controller and joining the conductor 140. The fingers 160 and 162 are bridged by a contact 163 when the hoist controller is in the 90 position for giving reverse power to the motor.

The controller position giving this reverse power to the motor is on the lowering side 95 of the controller, beyond the last lowering point, which gives the maximum lowering speed. To prevent the unintentional application of power to the hoist motor when lowering a load, an additional safety device is provided, in the form of a push-button switch 164 in the hoist controller handle, which must be pressed in order to close the circuit to the magnet for operating the reverse power switch, and which is operative only when 100 the hoist controller handle is in this extreme position. The circuit for the push-button switch 164, when the hoist controller handle is in the position for giving reverse power to the motor, and when the operator has pressed 110 this switch and also the push-button switch 148 on the rack controller handle, may be traced as follows: from the conductor L, by way of conductor 165 to the magnet 166 in the hoist control panel for operating the reverse 115 power switch, from said magnet to finger 167 and contact 168 by way of the conductor 169, and from contact 168 to contact 163 and finger 162, the said contacts being electrically connected through said push-button switch 164. From the finger 162 the circuit continues 120 through the conductors 161 and 140 to the rack controller, and through the latter, by way of push-button switch 148, and conductor 143 back to conductor L'. Of course, putting reverse power on the motor will not effect opening of the bucket, unless foot-pedal 125 156 is pressed to close the push-button switch 157 and operate the three-way valve 155, which effects release of the hold clutch and 130

hoist motor brake, leaving the hold brake applied.

In cases where the operator's cab is located at some distance from the engine house, as 5 on some rope system bridges, so that it is not convenient to lead the pressure fluid piping into the cab, the same feature of separate control of the hold brake may be obtained in a slightly different way. Instead of using 10 one magnet controlled valve for the hold brake and the hoist motor brake, one magnet controlled valve for each brake may be provided, controlled by one set of fingers and segments in the hoist controller. The foot-pedal 156, 15 in this case, instead of being used to operate a three-way valve, would be arranged to open the circuit leading from the hoist controller to the valve magnet for the hold brake, so that when the pedal was pressed, the controller 20 could release the motor brake, leaving the hold brake set. Thus the same control is obtainable as with the three-way valve arrangement previously described, it being possible to set the hold brake with the controller 25 in a position which normally releases it, but not to release it when the controller has it set.

The above description of the control system may be made more clear by taking up 30 in order the motions which the operator makes for a complete cycle of duty for the bucket in the normal operation thereof: Starting with the bucket resting on the coal, it is closed by moving the controller handle 35 to a hoisting position, and at the same time pressing the button on the rack controller handle which releases the hold clutch and permits the motor to wind up the closing ropes alone; and when the bucket is closed, it 40 is merely necessary to release the pressure on the button, permitting the hold clutch to set and turn the hold drum so that both sets of lines are taken in at the same rate and the bucket is hoisted. When the bucket is at the 45 desired height, power is shut off from the hoist by putting the controller handle in the "off" position, which also sets the motor brake and the hold brake. When the bucket has been carried by the trolley to the dumping 50 point, it is opened by pressing the foot-switch which releases the closing drum clutch, permitting the weight of the material in the bucket, through the pull on the closing lines, to turn the closing drum in the reverse direction. At the proper instant the foot-switch 55 is released, which sets the closing clutch again, stopping the spinning of the drum and leaving the bucket ready for lowering, open, which is done by moving the controller handle to any desired lowering point. This 60 releases both brakes, and the speed is controlled, as usual in this class of machinery, by dynamic braking or regenerative braking.

When it is desired to close the bucket in 65 the air or on a side slope where it tends to fall

over, the operator, in addition to pressing the button 148 on the rack controller handle as he moves the hoist controller handle to a hoisting position, will press the foot-pedal 156, whereby the motor brake alone will be released, leaving the hold brake set. If the operator desires to use reverse power on the hoist motor, he will press the button 148 on the rack controller handle and the foot-pedal 156, and will also press the button 164 on the hoist controller handle as he moves the hoist controller to the position for giving reverse power to the motor, which, as already explained, is on the lowering side of the controller beyond the last lowering point. 70 75 80

All of the brakes and clutches for controlling the operation of the bucket by the hoist motor are set by springs and released by fluid pressure, so that in case of failure of the pressure fluid supply, the clutches and brakes will be set and sustain the bucket and its load. It will also be apparent from the wiring diagram that the valve magnets are arranged to require current to release the brakes and clutches, so that failure of the current will 85 leave the brakes and clutches set, preventing dropping of the bucket or its contents. 90

For the control of the trolley motion, in case of direct current machines, the controller is usually arranged to provide dynamic braking to retard the motion of the trolley. While this has been very generally used, it has one inherent defect, this being that the braking effort on any one point of the controller varies in intensity with the speed, being greater at the higher speed and gradually losing force as the speed is reduced. Thus dynamic braking by itself produces a series of more or less abrupt peaks of braking effort, each followed by a gradual diminution of effort until the next point to which the controller is moved produces another peak. This is objectionable because it causes swinging of the bucket and discomfort to the operator if the peaks are perceptibly higher in braking effort than the intervals between the peaks, that is, unless the dynamic braking side of the controller has a very large number of control points. 100 105 110

The use of air brakes on the trolley motion, in addition to dynamic braking, as previously provided by other control systems, does something toward overcoming this objection to the use of dynamic braking alone, but has required the manipulation of an additional air valve and thus added one more control unit. 115 120

My invention as described below gives a more uniform degree of braking effort, and requires less manipulation on the part of the operator. It permits the use of a low fluid pressure for normal braking and a higher fluid pressure for emergencies without introducing an additional control unit to be handled by the operator. 125

The separate magnet controlled valves 120 130

and 121 are provided for the two fluid pressures. These inlet valves and the exhaust valve 118 are controlled by contacts in the rack controller. Referring again to the piping and wiring diagram, the numerals 1 to 6, inclusive, shown on the bottom portion of the rack controller drum, on each side thereof, represent different positions of the controller for power, coasting and braking, in either direction of travel of the trolley, 5 and 6 represent power positions, 4 the coasting position, and 1, 2 and 3 braking positions. The zero represents the neutral or "off" position of the controller. One side of each of the magnets 119, 122 and 123 is connected to conductor L by a conductor 170, and conductors 171, 172 and 173 lead from the other side of these magnets to fingers 174, 175 and 176 in the rack controller. Segments 177, 178 and 179 on the rack controller drum are electrically connected to the contact ring 147, and the latter is connected to the conductor L' through finger 144 and conductor 143. When the controller is in a power position, the fingers 174, 175 and 176 are in contact with the segments 177, 178 and 179 on one side or the other of the controller drum, depending upon the direction of travel of the trolley, and consequently the magnets 119, 122 and 123 are energized, so that the exhaust valve 118 is open, and the inlet valves 120 and 121 are closed, and hence the rack brake is released. On the coasting point (position 4), between the power and dynamic braking positions of the rack controller in each direction, the rack motor brake is released the same as on the power points of the controller. On the first braking point (position 3), the controller gives minimum dynamic braking, and the exhaust valve is closed, because finger 174, in this position of the controller, is not in contact with either segment 177, but the inlet valves remain closed. On the next or second braking point (position 2), the low pressure inlet valve is opened, because finger 176, in this position of the controller, is not in contact with either segment 179. As previously explained, this valve is fed through a pressure reducing valve 124, readily adjustable to give any desired pressure. This reducing valve, due to its construction, admits the pressure fluid rather slowly, so that the increase of pressure in the brake cylinder is somewhat gradual and approximately compensates for the gradual decrease of the dynamic braking, thus giving the trolley a more uniform retardation than is obtained with either kind of braking alone. If, on account of wet rails or any other reason, the operator desires to hold the braking effort uniform at a lower amount than that produced by the fluid pressure for which the reducing valve is set, the controller handle is moved back to the first braking point, where the inlet valve is closed, and where the ex-

haust valve, remaining closed, retains in the brake cylinder 111' the fluid pressure existing at the instant the inlet valve was closed. This is what is known as a "lap" position. In case the fluid pressure has increased above what the operator desires, moving the controller handle momentarily to the coasting position will permit him to make a slight reduction in the pressure, after which the desired pressure can be obtained by putting the handle again in the "lap" position. If a higher pressure, or a quicker increase in braking effort is needed, moving the controller handle to the last point (position 1) gives maximum dynamic braking, and at the same time opens the high pressure inlet valve, because the finger 175 is then not in contact with either segment 178. The adjustable choke valve 125 in the high pressure line can be regulated so that the rate of increase of pressure when the high pressure valve is opened will not be too rapid, as it is desirable to have the increasing of pressure in the cylinder of the rack brake occur at such a rate that the operator can stop the increase at any desired point.

The ability to obtain delicate and exact gradations in the braking effort on the trolley is of value, in that it enables the operator to bring the trolley to a stop at the desired point without making sudden or violent changes in the rate of retardation which cause swinging of the bucket and thus delay operations.

In the wiring and piping diagram I have not shown the electrical connections for the dynamic braking, as such connections are so well known that it is thought that to show them would not add to the clearness of the disclosure, but rather would confuse the diagram. I have also deemed it unnecessary to show the piping and wiring connections for the brake of the other rack motor, as these are obviously a duplicate of those shown. It will be understood, of course, that the wiring connections for both brakes are such that the same fingers and segments in the rack controller control both brakes.

This system of trolley braking provides the utmost degree of flexibility in controlling the application of braking effort, without requiring the use of any other control unit than the handle of the rack controller, and it is believed that it constitutes a material improvement over any control system that has previously been devised for the trolley-travel motors of coal and ore bridges and similar machines.

By the provision of this combined control system for the bucket and trolley motors, I have made it possible for the operator to control all the movements of the bucket and trolley without removing his hands from the two controller handles, and in regular operation where there is no tendency for the bucket to

tip over while closing, only one foot-operated switch is used in addition to the two control handles. On rope system machines it has a further advantage over previous control systems in that two control cabs can be placed at advantageous points, one for unloading or stocking, for example, and the other for reclaiming the material and loading it out, and this without requiring any mechanical operating levers or air pipes to extend from one cab to the other or from either cab to the engine house.

I claim:

1. Hoisting apparatus, comprising a drum, a motor for operating said drum, a controller for said motor, a fluid-pressure released brake for said drum, a valve for controlling the pressure fluid for releasing said brake, electrical means for actuating said valve, including contact means associated with and actuated upon movement of said controller, and a valve for preventing release of said brake by said pressure fluid when said first-mentioned valve is actuated by said electrical means, substantially as described.

2. Hoisting apparatus, comprising a drum, a motor for operating said drum, a controller for said motor, a fluid-pressure released brake for said drum, a fluid-pressure released brake for said motor, a valve for controlling the pressure fluid for releasing both brakes, electrical means for actuating said valve, including contact means associated with and actuated upon movement of said controller, and a valve for preventing release of the first-mentioned brake by said pressure fluid when said first-mentioned valve is actuated by said electrical means, substantially as described.

3. Hoisting apparatus, comprising a drum, a motor for operating said drum, a controller for said motor, a clutch associated with said drum, and electrical means for controlling said clutch, including contact means associated with and actuated upon movement of said controller, and a switch, said switch being effective to close the circuit for controlling said clutch only when said controller is in the "off" position, substantially as described.

4. Hoisting apparatus, comprising a trolley, a drum, a rack motor for operating said trolley, a hoist motor for operating said drum, a clutch associated with said drum, a controller for each of said motors, and electrical means for controlling said clutch, including contact means associated with and actuated upon movement of said hoist controller, and a switch operable from the rack controller handle, substantially as described.

5. Hoisting apparatus, comprising a trolley, a drum, a rack motor for operating said trolley, a hoist motor for operating said drum, a clutch associated with said drum, a controller for each of said motors, and electrical means for controlling said clutch, including contact means associated with and actuated

upon movement of said hoist controller, and a switch operable from the rack controller handle, said switch being effective to close the circuit for controlling said clutch only when said hoist controller is in a hoisting position, substantially as described.

6. Hoisting apparatus, comprising a trolley, a pair of drums, a rack motor for operating said trolley, a hoist motor for operating said drums, a clutch associated with each of said drums, a controller for each of said motors, and electrical means for controlling said clutches, including contact means associated with and actuated upon movement of said hoist controller, a switch in the circuit for controlling one of said clutches, and a switch in the circuit for controlling the other of said clutches operable from the rack controller handle, substantially as described.

7. Hoisting apparatus, comprising a trolley, a pair of drums, a rack motor for operating said trolley, a hoist motor for operating said drums, a spring-applied and fluid-pressure released clutch associated with each of said drums, a controller for each of said motors, and electrical means for controlling the pressure fluid for releasing said clutches, including contact means associated with and actuated upon movement of said hoist controller, a switch, and a switch operable from the rack controller handle, substantially as described.

8. Hoisting apparatus, comprising a drum, a motor for operating said drum, a controller for said motor, and a switch operable from the controller handle forming part of the circuit for giving reverse power to said motor, said switch being effective to close said circuit only when said controller is in its last lowering position, substantially as described.

9. Hoisting apparatus, comprising a pair of drums, a motor for operating said drums, a controller for said motor, a clutch associated with one of said drums, electrical means for operating said clutch, a switch operable from the controller handle forming part of the circuit for giving reverse power to said motor, and a switch forming part of the circuit for operating said clutch, said switches being effective to close said circuits only when said controller is in its last lowering position, substantially as described.

10. Hoisting apparatus, comprising a pair of drums, a motor for operating said drums, a controller for said motor, a clutch associated with one of said drums, a brake for said drum, electrical means for effecting release of said clutch and brake, including contact means associated with and actuated upon movement of said controller, a normally open switch in the circuit for releasing said clutch, and means for simultaneously closing said switch and rendering said electrical means ineffective to release said brake, said switch

being effective to close said circuit only when said controller is in the position for giving reverse power to the motor, substantially as described.

- 5 11. Hoisting apparatus, comprising a pair of drums, a motor for operating said drums, a controller for said motor, a clutch associated with one of said drums, a brake for said drum, electrical means for effecting release 10 of said clutch and brake, including contact means associated with and actuated upon movement of said controller, a normally open switch operable from the controller handle forming part of the circuit for giving reverse power to the motor, a normally open switch in the circuit for releasing said clutch, and means for simultaneously closing the last-mentioned switch and rendering said electrical means ineffective to release said 15 brake, said switches being effective to close said circuits only when said controller is in its last lowering position, substantially as described.

12. Hoisting apparatus, comprising a hold 25 drum, a closing drum, a motor for operating said drums, a controller for said motor, a clutch operatively connecting each drum to said motor, a brake for said hold drum, electrical means for effecting release of the brake 30 and hold clutch, including contact means associated with and actuated upon movement of said controller, a normally open switch in the circuit for releasing said hold clutch, and means for simultaneously closing said switch

and rendering said electrical means ineffective to release said brake, substantially as described.

13. Hoisting apparatus, comprising a trolley, a drum, a rack motor for operating said trolley, a hoist motor for operating said drum, a clutch operatively connecting said drum to said hoist motor, a controller for each of said motors, and electrical means for effecting release of said clutch, including a normally open switch operable from the rack controller handle and a second normally open switch, the switch on the rack controller handle being effective to close the circuit for releasing said clutch only when the hoist controller is in a hoisting position and the second switch being effective to close said circuit only when said controller is in a position for giving reverse power to the hoist motor, substantially as described.

14. Hoisting apparatus, comprising a trolley, a drum, a rack motor for operating said trolley, a hoist motor for operating said drum, a clutch associated with said drum, a controller for each of said motors, and electrical means for controlling said clutch, including contact means associated with and actuated upon movement of said hoist controller, and a switch operable from the rack controller handle but independent of the rack control, substantially as described.

In testimony whereof I have hereunto set my hand.

RAYMOND E. BROWN.
